UNITED STATES PATENT OFFICE.

CHARLES H. GARDNER, OF KANSAS CITY, MISSOURI, ASSIGNOR TO STANDARD OIL COMPANY (OF INDIANA), OF WHITING, INDIANA, A CORPORATION OF INDIANA.

TANK-WAGON.

1,324,548.

Specification of Letters Patent.

Patented Dec. 9, 1919.

Application filed June 9, 1919. Serial No. 302,781.

To all whom it may concern:

Be it known that I, CHARLES H. GARDNER, a citizen of the United States, residing at Kansas City, in the county of Jackson and 5 State of Missouri, have invented a new and useful Improvement in Tank-Wagons, of which the following is a specification.

My invention relates to an improvement in the class of delivery wagons, whether of 10 the horse-drawn or tractor types, and commonly designated "tank-wagons" in the petroleum industry, wherein they are employed for dispensing along their routes to retail dealers, garages and consumers supplies of gasolene, kerosene, lubricating oil, 15 and other commodities.

In the accompanying drawing, which exhibits only so much of a motor-driven tank-wagon as is needed to show my improvement, the running-gear being therefore omitted, Figure 1 is a view in side elevation of the vehicle provided with my invention, and Fig. 2 is a section on line 2--2, Fig. 1.

The tank 3, of ordinary or any desired 25 construction and provided with buffer-strips at 3^a, is strapped, as usual, on carrying bolsters 4, of which the three shown are commonly used for supporting the tank on side-sills 5 of a truck (not shown). Platforms 30 6, 6 on the bolsters extend outwardly from opposite sides of the tank near its base, and have stops or abutments 7 rising from near their opposite ends the abutments shown being of gas-pipe and each formed of a pair 35 of spaced vertical-legs and a cross-piece connected with the upper ends of the legs by elbows 8. To the outer edge of each platform is connected, by a hinge 9, a gate 10 having reinforcing cleats 11 on its inner face 40 and extending substantially throughout the length of the tank. At equal intervals along each gate bifurcated catches 12 project from its outer edge to engage chains 13 having their inner ends fastened by clips 14 to the

body of the tank at its top-portion. Hooks 45 are shown at 15 to engage eyes 16 on the upper cleats 11 for rigidly spacing from the abutments the gates in their normally upright position, besides supplementing the chains in holding them against unfolding 50 from that position.

The purpose of the platforms with the end-abutments and gates is for carrying under confinement small packages of commodities, such as cans of lubricating oils, for 55 supplying customers therefor from the tank-wagon. It is often required, however, to carry oil to customers in barrels of different capacities, and it is a primary object of my improvement to adapt the tank-wagon for 60 the purpose. To that end the gates 10 are hinged, as shown and described, to adapt them to be adjusted to extend upwardly at any desired angle to the platforms and thereby expand the space between each gate 65 and the adjacent side of the tank to accommodate on the platforms barrels of different sizes and confine them between the end-abutments 7, the gates and the tank-sides; and the chains 13 are provided for readily but 70 securely fastening the gates in adjusted position and in a manner for permitting them to be readily released and lowered to permit convenient unloading from the platform.

I claim:

In combination with a tank-wagon having platforms extending from opposite sides of the tank-bottoms and abutments on the platform-ends, gates hingedly connected with the outer platform-edges for adjustment to 80 expand the space between each and the adjacent tank-side, chains on the tank for engaging the gates and holding them in adjusted position, and hook-and-eye connections between the abutments and gates and 85 from the abutments.

CHARLES H. GARDNER.
